EASEL BRACKET

Filed Feb. 13, 1928

Inventor:
John W. Dixon,
By *John W. Dixon*
Attest:
John W. Dixon

UNITED STATES PATENT OFFICE.

JOHN W. DIXON, OF MAYWOOD, ILLINOIS.

EASEL BRACKET.

Application filed February 13, 1928. Serial No. 253,861.

This invention relates to easel brackets, and has been designed primarily for use in connection with printed or lithographed advertising displays, such as posters, pictures, 5 calendars, and the like, which are printed upon limp paper, cloth, or the like, and hence lack the requisite body or stiffness to render them self-supporting.

One of the objects of the present invention 10 is to provide improved means for connecting the easel bracket to the printed sheet. Another object is to simplify, cheapen and otherwise improve upon the construction of easel brackets. Another object is to provide an 15 easel bracket which may be easily assembled for use and disassembled for storage or shipment.

Another object is to provide improved 20 means for adjustably connecting the leg member of the easel with the other supporting members thereof, whereby the leg member may be readily extended into a position for supporting the easel, and whereby the leg member may be readily moved back against 25 the other members, so that the entire easel may occupy but little space for storage or shipment. Another object is to provide an extensible supporting element between opposite edges of the sheet and having resilient 30 means for holding the members of the supporting element in extended position, whereby the sheet may be stretched taut.

Other objects and advantages will appear 35 in the course of this specification, and with said objects and advantages in view, this invention consists in the several novel features of construction, arrangement and combinations of parts hereinafter fully set forth and claimed.

40 The invention is clearly illustrated in the drawing accompanying this specification in which—

Figure 1 is a perspective view of an easel bracket embodying a simple form of the present invention and showing the same in position supporting a display sheet;

Fig. 2 is a rear elevation of the easel, on an enlarged scale, with certain members, partly broken away;

50 Fig. 3 is a detail vertical cross section taken on the line 3—3 of Fig. 2;

Fig. 4 is a detail vertical section taken on the line 4—4 of Fig. 2;

55 Fig. 5 is a detail cross section taken on the line 5—5 of Fig. 2; and

Fig. 6 is a detail vertical cross section taken through the foot of the leg member of the easel.

Referring to said drawing, which illustrates a simple embodiment of the present 60 invention, the reference character 10 designates a rectangular sheet of paper, cloth, or the like, one of both sides of which is arranged to receive printed matter, such as posters, pictures, calendars, or other display 65 advertisements. Secured to the upper and lower edges of the sheet 10 are metallic binding strips 11, each of which is folded around and upon an edge portion of the sheet, as is clearly seen in Fig. 4, and is flattened down 70 upon itself to effectively grip the edge portion and provide a stiffening member therefor.

Secured to the binding strips 11 are oppositely extending tongues 12 which may be formed of light gauge sheet metal. Said 75 tongues may be fastened in place between the rolled or folded together parts of the binding strips. The tongues are formed with outwardly struck up loops 13 which are adapted to receive tongues 14 formed on the ends of 80 the sheet supporting member which is illustrated at 15. The tongues 14 are made slightly narrower than the supporting member, whereby shoulders are formed at the ends of said supporting member that engage with 85 the edges of the loops, as is clearly seen in Fig. 2.

The supporting member 15 is made telescopic whereby it may be extended and contracted for the purpose of effecting its engagement with the tongues 12. As shown, 90 the supporting member comprises two channel shaped bars 16 and 17 formed of light gauge sheet metal, the flanges 18' of which converge slightly towards each other, as seen 95 in Fig. 5, to afford the telescopic connections between them.

Resilient means are provided between the two bars for moving them in opposite directions, lengthwise of each other, and, as shown, 100 said means comprise a coiled tension spring 18, one end of which is secured to a bent up hook member 19, or other anchoring element, on the bar 17, and the other end of the spring is secured to a bent up hook or anchoring member 20 on the bar 16. The bar 16 is formed with a slot 21 which extends lengthwise of the bar, and the hook member 19 projects through said slot so as to lie on the same side 105 of the supporting member as the hook mem- 110

ber 20. Both of said hook members and the spring are preferably contained in the channel of the supporting member.

The hook members are formed in the parts 5 of the channel bars that overlap each other, and each hook member is formed adjacent the end of the bar farthest removed from its point of connection with the binding strip, whereby the tension of the spring is exerted 10 to extend the bars and thereby hold the ends of the bars in locking engagement with the tongues 12 and to stretch the sheet taut. The supporting member is secured to the tongues 12 by telescoping the two members 16 and 17 15 far enough to permit the ends thereof to be inserted underneath the loops 13.

The leg member 22, also formed of light gauge sheet metal of channel formation, is employed as a brace for the easel, and said leg 20 member is secured to the upper bar 16 of the supporting member 15 by a rivet 23, which is preferably in the form of a hollow rivet. The neck or shank of the rivet extends through a hole in one of the channel bars and 25 through a slot 24 formed in the leg member 22. The upper end portion 25 of the leg member is bent at an angle to the main portion, whereby when the leg is placed in its angularly disposed supporting position, said upper end 25 may lie parallel and contiguous with the bar 16. The leg member 22 nests into the channel of the channel bar 16 and its upper end may be formed with a tongue 26 narrower than the main portion of the leg member, which tongue 30 is arranged to be inserted behind a loop 27 struck up from the bar 16. The slot 24 permits the leg member to be moved downwards to disconnect it from the loop 27 and also allows the leg member to be moved upward until 40 the main portion thereof may be laid approximately parallel with the supporting member. This is done when the parts are packed for shipment. The lower end of the leg member may be bent transverse to form 45 a foot 28, around which may be placed a rubber ferrule 29 which prevents the foot from scratching the surface upon which the easel is placed.

Inasmuch as the metal parts of the easel are 50 preferably formed of very light gauge sheet metal, the channel formation of the supporting members and leg members affords a very rigid and substantial structure. The provision of the coiled tension spring for extending 55 the two parts of the supporting member provides a simple and convenient means for holding the supporting member in locking engagement with the binding strips and also acts to hold the sheet in a taut condition. 60 With the use of the rivet connection between the supporting member and leg member, the leg member is positively connected to the supporting member, but may be readily adjusted to its supporting position or to its folded or collapsed condition. When the support-

ing member and leg members are folded together, the sheets may be rolled around the same and placed in a mailing tube for shipment. The parts are extremely light and yet strong and rigid, and provide a very substantial easel bracket for supporting posters, calendars and other advertising displays.

More or less variation of the exact details of construction is possible without departing from the spirit of this invention. I desire, therefore, not to limit myself to the exact form of the construction shown and described, but intend, in the following claims, to point out all of the invention disclosed herein.

I claim:

1. In an easel bracket, telescoping supporting members, a leg member adapted for adjustment in obliquely extended relation to the supporting members and having a slotted upper end portion, including a part intermediate the ends of the slot extending at an angle to the main portion of the leg and adapted to lie contiguous with one of the supporting members, said angularly disposed end portion being relatively short as compared with the length of the leg and a rivet secured in one of said supporting members and extending through said slot.

2. In an easel bracket, two telescoping supporting members, both of channel formation and both having interlocking converging side flanges, a leg member of channel formation adapted for adjustment in obliquely extended relation to the supporting members, said leg member having a slotted upper end, having a part intermediate the ends of the slot, disposed at an angle to the main portion of the leg member and adapted to nest into said supporting members, and a rivet secured in one of said supporting members and extending through said slot.

3. In an easel bracket, telescoping channel shaped supporting members formed with interlocking converging side flanges, one of which supporting members is formed with a struck up loop, a leg member nested into one of said channel shaped supporting members adapted for adjustment in obliquely extended relation to said supporting members and having a slotted upper end portion formed with a tongue adapted to enter said loop, said upper end portion being angularly disposed with respect to the remainder of the leg member, and a headed connecting member secured to one of said supporting members and extending through the slot in said leg member.

4. The combination of a sheet of material having binding strips secured on two of its opposite edges, tongues, one secured to each binding strip and extending toward the other tongue, each tongue being formed with a struck up loop, a longitudinal extensible supporting member formed with side flanges and having a tongue on each end beyond said side flanges adapted for insertion into said side flanges.

loops with the ends of the side flanges abutting against the loops, and a leg member adjustably secured to said supporting member.

5. The combination of a sheet of material having binding strips on two of its opposite edges, tongues, one secured to each binding strip and extending toward the other tongue, each tongue being formed with a struck up loop, a two part extensible supporting member having tongues on its ends adapted to be inserted into said loops, resilient means for extending the two parts of said extensible supporting member, and a leg secured to said supporting member.

15. 6. The combination of a sheet of material having binding strips on two of its opposite edges, tongues, one secured to each binding strip and extending towards the other tongue, each tongue being formed with a struck up loop, two telescoping channel shaped bars forming an extensible supporting member, each bar having a tongue formed on its outer end adapted to be inserted into the loop of one of the tongues on the binding strip, resilient means connected to said channel bars and arranged to extend them in opposite directions, and a channel shaped leg member adjustably secured to one of said channel bars.

30. 7. The combination of a sheet of material having binding strips secured upon two of its opposite edges, tongues, one secured to each binding strip and projecting toward the other tongue, each tongue being formed with a struck up loop, upper and lower channel shaped supporting bars telescoping one into the other, and a coiled tension spring extending lengthwise of the supporting bars and having one end secured to one bar and the

other end secured to the other bar, whereby the supporting bars are extended in opposite directions.

8. The combination of a sheet of material having binding strips upon two of its opposite edges, slotted tongues extending from said binding strips, two channel shaped bar members, the one telescoping into the other and arranged for connection with said tongues, said channel bars being formed with anchoring members arranged at one side of the bar members, one of said bar members being formed with a slot through which the anchoring member of the other bar member extends, and a coiled tension spring, the ends of which are secured upon said anchoring members.

9. In an easel bracket, two telescoping channel shaped supporting bars formed with interlocking converging side flanges and a channel shaped leg member having an angularly bent slotted end portion adapted to nest into the channel of one of said channel bars, and a headed connecting member on one of said channel bars and entering the slot of the leg member.

10. In an easel bracket, two telescoping supporting bars of channel formation having interlocking converging side flanges, means for holding said bars in extending position, a leg member of channel formation having an angularly bent end portion nested in the channel of one of said channel bars, there being a slot in said bent up end portion of the leg member, and a headed fastening member secured in one of the channel bars and extending through the slot of the leg member.

JOHN W. DIXON.
